UNITED STATES PATENT OFFICE.

CLINTON O. MIKLE, OF PORTLAND, OREGON.

WEED-BURNING DEVICE.

Application filed August 22, 1924. Serial No. 733,540.

This invention while primarily for the purpose of destroying weeds, grass, etc., along the right of way of railroads, is like other apparatus of a like character adaptable to the melting of snow and ice along the tracks and for other purposes and proposes in a general way the use of a bank of fuel oil burners utilized in connection with a flame director and an adjustable apron, the 10 flame director intensifying the heat and the apron confining and directing such heat to the point of use.

More particularly my invention has to do with the above burner, flame director and apron, whereby they may be utilized, controlled, adjusted and actuated with the object in view of producing an effective and efficient apparatus without unnecessary complications.

With this general statement in mind, the invention including its several parts, their objects and advantages, will be better understood from the following detailed description thereof, reference being made to 25 the accompanying drawings which form a part of this specification, and in which,

Figure 1 is a side view of so much of the complete apparatus as directly concerns my present improvements,

Figure 2 is a top plan view thereof,

Figure 3 is a vertical transverse section taken on line 3—3 of Figure 2,

Figure 4 is an enlarged longitudinal section through the apron,

Figure 5 is a partial transverse section therethrough,

Figure 6 is a partial longitudinal section through the apron adjacent to one of its hinges,

Figure 7 is a side view, partly in elevation and partly in section, showing one of the expansion joints,

Figure 8 is an end view of the flame director,

Figure 9 is a sectional top plan view thereof,

Figure 10 is a transverse section taken therethrough,

Figure 11 is a sectional side view of the controlling ratchet of the apron.

Referring now especially to the general device as best seen in Figures 1, 2 and 3, my invention proposes certain improvements in an apparatus which is mounted upon a wheeled frame 20, the wheels thereof, for railroad use being adapted to travel

upon railway tracks so that the frame may be attached to a locomotive for traction purposes and may receive power from such locomotive for the operation of the different appliances comprising the apparatus, or preferably may have a boiler of its own, for either or both of the aforesaid purposes, a portion of such boiler being shown at 21.

At its rear end, frame 20 has an upper inverted U-shaped supporting bracket 22 best seen in Figure 3, and also has depending vertical straps 23, the latter terminating at their lower ends in apertured hinged ears 24. To these ears are connected the similar ears 25 of straps 26 securely fastened to the forward portions of the upper plate 27 of a rear hollow apron seen at 28 whose lower plate 29 is connected to the upper plate in spaced apart relation by a series of stud bolts 30, the surrounding edges of the two plates being turned upwardly to form flanges 31 as best seen in Figures 4, 5 and 6, or otherwise lapped or joined together whereby they may be riveted, welded or otherwise connected to form the desired water space within this apron.

Water is circulated constantly through the water space or chamber within the apron 28 by means of water circulating pipes 32, certain of which extend from the upper forward portion of the apron 28, to the upper rear portion of the same and across the rear portion, being connected thereto by apertured flanges to form a passage for low temperature water to enter apron 28, and other circulating pipes as at 33 extending across the upper forward portions of the apron and through the apertured ears 24 and 25 so as to thus form pintles for the hinges of the apron permitting the latter to be swung upwardly and downwardly at the rear of the main frame 20. In order to control the elevation of the apron in its generally horizontal active position in use as well as to draw the apron upwardly to vertical inactive position when not in use, the upper rear portion of the apron has spaced eye blocks 34 to which are attached the rear ends of cables or other flexible connections 35, the forward ends of which are disposed around sheaves 36 of considerable diameter, mounted upon a cross shaft 37 in connection with smaller sheaves 38.

The cross shaft 37 is mounted in bearings 39 upon upright longitudinally disposed

bearing frames 40 disposed lengthwise of the main frame 20, which bearing supports also carry the bed plates 41 of a pair of forwardly and downwardly inclined power cylinders 42, the latter having forwardly extending piston rods 43 connected to a cross beam 44. This cross beam is equipped at its opposite ends with rollers 45 disposed upon guide rails 46, the cross beam 44 having at opposite sides of the cylinders 42 a pair of shackles 47 to which the forward ends of cables or flexible connections 48 are joined. The rear ends of these cables are attached to the sheaves 38 beforementioned so that it is thus obvious in view of the difference in diameter between the sheaves 36 and 38 a differential action is set up resulting in relatively greater movement of the apron as compared to the movement of the pistons and rods within the cylinders 42. These cylinders are supplied with power through pipes 49 from a steam pump 50 under suitable valved control of course, the steam to operate steam pump 50 being supplied from the boiler to which the circulating pipes of the apron 28 are connected so that the apron is not only constantly water cooled but the water heated therein is utilized in the boiler. In other words the apron 28 is constantly cooled and acts as a feed water heater.

Intermediate its ends the cross shaft 37 supporting the sheaves 36 and 38 is provided with a ratchet wheel 51 seen in Figures 2, 3 and 11, engaged by a dog 52 so that the apron 28 is thus supported in any desired position without strain upon its adjusting parts with the exception of the cables 35.

On account of expansion and contraction of the parts it is preferable that the circulating pipes 32 at certain points in their connection with the apron 28 will embody expansion joints, one of which is generally indicated in Figure 2 and includes a three-way casing 53 as plainly seen in Figure 7 into the pair of opposing ports of which sections of the pipes 32 are movably held by packing glands. This joint also permits sections of the pipe connections to rotate when the apron is adjusted by virtue of its adjusting connections previously described and it is obvious that these joints may be placed wherever necessary and other joints of a similar nature employed wherever their presence becomes necessary.

Depending from the rear side portions of the main frame 20 are vertical guide straps 54 seen in Figures 1 and 8, these guide straps passing through the end brackets or guides 55 of a pair of castings 56 which together form an elongated flame director for the main bank of burners, said flame director being disposed transversely preferably beneath the rear portion of the main frame 20 and forwardly of the apron 28.

The castings 56 forming the flame director are lined with refractory material as indicated at 57 in Figure 10 and form between these refractory linings 57 a downwardly and rearwardly opening and gradually enlarging flame channel 58, the rear portion of which opens beneath the forward portion of the apron 28 and opposite the forward portion of which a series of burners 59 are disposed. These burners utilize a mixture of steam and oil and the flame therefrom through their nozzles 60 is directed into the forward side of the flame channel of the flame director and confined and guided by the latter in a downward and rearward direction below the apron 28 the latter of which in turn confines the heat to the points where it is needed and desired.

The castings 56 forming the flame director are also provided with slotted ventilating openings 61 so as to defeat tendency to warp and crack, and these castings also form a flame director having a flame channel whose downwardly and rearwardly enlarging shape creates a suction through the flame channel so as to draw air therethrough and greatly intensify the heat and add to the efficiency of the weed burning or snow and ice melting operation. The flame director as a whole is supported by uprights 62 projecting upwardly through the main frame and connected as shown in Figure 1 to the piston rods 63 of power cylinders 64 supplied with fluid below the piston thereof by means of pipes, one of which is seen at 64¹ in Figure 1 and it is obvious from this that the flame director as a whole may be moved vertically upon the depending guide straps 54 beforementioned. The flame director is also provided with spaced angle bars 65 having bearings 66 at their free ends for the end trunnions 67 of a burner supporting beam 68, the latter extending parallel to the upper front face of the flame director adjacent to the upper forward side of the flame channel 58 and being secured to and forming a pivotal support for the series of main burners 59. Thus in the adjustment of the flame director the series of burners 59 will follow its movement although these burners are at all times subject to adjustment on the axis of the supporting bar or beam 68 so that their nozzles 60 may be adjusted vertically and laterally in the upper forward portion of the flame channel 58 of the flame director.

The several burners 59 which form the main bank of burners are supplied with steam and oil through flexible connections 69 seen in Figure 1 from supply pipes 70 best seen in Figure 2, the latter leading rearwardly from oil and steam headers 71 and 72 also shown in Figure 2, provided with suitable valves controlling the flow of oil and steam to the various pipes leading therefrom.

The main bank of burners 59 directing

their flames into and through the flame director are furthermore utilized in connection with burners 73, at each side of and below the main frame, adjacent to and forwardly of the ends of the flame director. These side burners 73, each include a downwardly directed nozzle 74, and are secured to the rear end of the steam supply pipe 76 of the burner as well as the rear end of the oil supply pipe 77 which extends axially within the steam pipe 76. The burner 73 is pivotally supported and the steam and oil tubes 80 and 81 are swivelly connected so that each burner 73 may thus be tilted in a vertical plane so as to vary the position of its downwardly directed nozzle 74. To each nozzle is pivotally secured the rear end of a connecting rod 82 whose forward end is similarly connected to an adjusting spool 83 slidable on the forward portion of the steam supply pipe 76 and controlled by virtue of its engagement by the lower forked end 84 of an upright adjusting lever 85 having a latch mechanism 86 in engagement with a notched quadrant 87 on the main frame 20, this adjustment of the burner 73 obviously shifting the burner in a vertical plane lengthwise of the machine. In addition, the steam and oil supply pipes 76 and 77 are rotatable in forward and rear bearings 88, the former of which is swiveled in connection with a support 89 on the main frame 20 so that the rear portions of these pipes may be raised and lowered with the burners 73 for which purpose the rear bearings 88 are adjustably disposed in apertures 90 of a bracket 91 depending from the main frame 20. Moreover the steam and oil supply pipes 76 and 77 being rotatable in their bearings and having rotatable connections with their forward connecting joints 92, the burner 73 may be shifted in a vertical plane laterally of the machine for which purpose the forward portion of the steam pipe 76 has clamped thereto a ring 93 to which is pivotally joined the lower end of a connecting rod 94 whose upper end is pivotally connected to the lower angular arm 95 of an upright controlling lever 96 provided with a suitable latch mechanism adapted to engage a suitable notched quadrant mounted on the main frame 20.

In this way it is obvious that the side burners 73 may not only be raised and lowered but may be swung on their swivel supports in vertical planes both longitudinally and transversely of the machine so that the flames from their nozzles 74 may be directed at just the desired points as for instance the rails themselves, to supplement the action of the main bank of burners operating through the flame director.

It is furthermore obvious that I am enabled in this way to increase the effectiveness and efficiency of the machine as a whole

in so far as the results of the weed burning operation as well as the snow and ice melting operation are concerned.

The machine as a whole is of course drawn along the right of way in any suitable manner as for instance by means of a locomotive the boiler of which may be utilized as a source of supply for the steam fed to the several burners as well as to the cylinders for adjusting the apron and the flame director but as before stated my invention contemplates the use of a separate boiler mounted on frame 20 and connected with the apron so that the latter, absorbing as it does a great amount of the heat of the main bank of burners, which would otherwise be wasted, will form a feed water heater for the boiler, the water passing through the apron for this purpose also functioning to cool the apron at all times by absorbing a portion of the heat.

My invention presents moreover a machine for this purpose which is practical and highly efficient, which is strong and durable, and which is without unnecessary complications and is in fact simple as compared to other machines for a similar purpose when its results and its general effectiveness and efficiency are taken into consideration.

I claim:

1. An apparatus of the character described including a wheeled frame; a source of steam supply in connection therewith; burners connected to the source of steam supply and supported beneath the rear portion of the frame; a fuel supply for said burners; an apron hinged to the rear portion of the frame and beneath which the burners discharge; fluid circulating means in connection with said apron for cooling the same and supplying heated feed water to said source of steam supply; and a flame director transversely of the frame, between the burners and said apron and having a rearwardly enlarging and downwardly inclined flame channel.

2. An apparatus of the character described including a wheeled frame; a source of steam supply in connection therewith; burners connected to the source of steam supply and supported beneath the rear portion of the frame; a fuel supply for said burners; an apron hinged to the rear portion of the frame and beneath which the burners discharge; fluid circulating means in connection with said apron for cooling the same and supplying heated feed water to said source of steam supply; a flame director transversely of the frame, between the burners and said apron and having a rearwardly enlarging and downwardly inclined flame channel; and means for adjusting the said flame director and the said burners vertically with respect to the said apron.

3. An apparatus of the character described including a wheeled frame; a source of steam supply in connection therewith; a series of burners utilizing steam from said source; a fuel supply for said burners; a hollow apron arranged to confine beneath the same the heat from said burners; fluid circulating pipes in connection with said apron for circulating water through the hollow portion thereof, the said pipes being connected to the source of steam supply of the burners for supplying heated water from the apron to said source of steam supply; and a flame director transversely of the frame between the said burners and said apron.
- 10 4. An apparatus of the character de-

scribed including a wheeled frame; a source of steam supply in connection therewith; a series of burners utilizing steam from said supply; a fuel supply for said burners; a heat confining apron arranged to confine beneath the same the heat from said burners and having therein a fluid chamber; circulating pipes for supplying water to said chamber to absorb heat from the apron, said pipes being connected to the source of steam supply for feeding heated water to the latter from the apron; and a flame director transversely of the frame between the said burners and said apron.

15 In testimony whereof I hereunto affix my signature.

CLINTON O. MIKLE.
